TORQUE AMPLIFYING SYSTEM

Nicholas Minorsky, Bethesda, Md., assignor, by
mesne assignments, to Lear, Incorporated,
Grand Rapids, Mich., a corporation of Illinois

Application October 26, 1945, Serial No. 624,772

10 Claims. (Cl. 114—144)

1 This invention relates to torque amplifying devices, and more particularly to such arrangements in which a relatively small force or torque is proportionately amplified. Regarded in one aspect the invention has for a principal object the provision of a steering gear for a dirigible craft capable of the advantages of a purely manual control of the rudder while utilizing force amplification in the operation thereof.

“Purely manual control” as alluded to in the foregoing paragraph is intended to mean those cases wherein the rudder is connected directly to a steering wheel by cables in the simple, conventional manner without the interposition of an auxiliary source of power such as a steering engine provided with a follow-up attachment. With the foregoing type of control the helmsman, when he desires to turn the ship, rotates the steering wheel, applying a gradually increasing effort as the rudder angle increases. If the helmsman, after having introduced a selected rudder angle, removes his hands from the wheel, the hydrodynamic pressure of the water particles on the rudder tends to return the rudder to its middle position, and since the rudder is directly connected to the steering wheel, the latter likewise returns to its middle position. Obviously the situation just recited fails to exist where there is provided a steering engine including a follow-up attachment. In this case, if the helmsman, after having introduced a predetermined rudder angle, removes his hands from the wheel, the rudder does not spontaneously return to its middle position. Such end can be brought about only by movement of the wheel to its middle position by the helmsman. For this reason, installations including a steering engine must be provided with a rudder angle indicator as the helmsman is without “feel” as to the then existing rudder angle.

Having pointed out the significance of the words “purely manual control,” there will now be briefly described the manner in which the instant invention achieves the advantages thereof, together with power actuation of the rudder. It is well-known that if a few turns of a cable are wrapped around a cylindrical drum with some initial tension, i. e. not loosely, and both ends of the cable are secured to suitably fixed points, a subsequent steady rotation of the drum with incident slipping of the cable on the drum surface, will produce a substantial difference in the tension of the two ends of the cable. If it is agreed to define that end of the cable toward which the surface of the drum is caused to rotate as “the

5 input end,” and that end away from which the drum surface is rotating as “the output end,” and specify that the respective different cable tensions as f and F it is easy to show that

$$F = fe^{\mu\alpha}$$

where μ is the coefficient of friction of the cable with respect to the drum, α is the angle over which the cable is wrapped, and e is the base of natural logarithms. Since the exponential function is always greater than unity, and, for a sufficiently large value of the exponent may be made a very large number, it follows that F may be made many times greater than f . The principle just outlined is utilized in the invention system.

10 If, instead of referring to the forces F and f , one considers the moments of such forces about the axis of the drum, the foregoing discussion may be referred to equally as torque amplification.

20 Moreover, if, in lieu of securing the ends of the cable fixed supports, these ends are connected to elements of a system to which forces can be applied it will be clear that a small force 25 at the input end can be effective to yield a much larger force at the output end, the two forces always being in the ratio

$$\frac{F}{f} = e^{\mu\alpha}$$

30 It will also be apparent that if the points at which the respective forces act are free to move there will exist power amplification as well, and that the power amplification will have a value 35 equal to the ratio of the forces or of the torques. Such increase in power at the output end will be supplied by the source used to rotate the drum.

Now turning to the invention arrangement, the drum, instead of being connected rigidly and 40 constantly to a power source, is driven through a clutch, preferably of the slipping disc type. In some well-known forms of such clutches the magnitude of the pull-out torque is substantially proportional to the pressure with which the clutch discs are held in contact, and such pressure may be produced by an electro-magnet having an armature to which one disc is secured, for example, as disclosed in United States Letters Patent No. 2,267,114, granted to William P. 45 Lear on December 23, 1941. Since the pressure with which the clutch discs are held in contact is substantially proportional to the exciting current, it is possible, by controlling the latter, to control the transmitted torque. In the invention system means are provided for controlling 50

the clutch excitation current in response to the tension prevailing in the input end of the cable. Accordingly I provide, in the input end of the cable, a tension-measuring device which is effective in turn to control the electrical input to the clutch coil. The arrangement is such that for a large input tension the exciting current is large. Under this condition the drum will be rotated, the above-mentioned relation between the forces f and F will be established, and the force F will 10 act on the rudder to produce a gradually increasing hydrodynamic force thereagainst. When that value of the moment due to the hydrodynamic reaction is reached which is equal to F , the rudder will stop at the angle then occupied. Such result is equivalent to that obtained with purely manual control, but with 15 rudder position maintained by the helmsman's grasp of the wheel.

If the clutch excitation is now reduced or removed entirely, corresponding to the reduction or absence of force exerted by the helmsman in the manual case, the drum becomes free and the forces f and F disappear. Accordingly the only force acting on the wheel is the hydrodynamic reaction on the rudder. Thus such reaction will 20 restore the rudder to streamline position, i. e., stable equilibrium, and likewise the steering wheel.

The invention is particularly applicable to 30 installations in which a relatively small manual control force is applied to control a relatively large power force in correspondence therewith. Typical examples of such systems are power steering systems for water borne vessels and aircraft, industrial applications such as cranes and hoists, and other similar arrangements. In many installations, such as yachts, tugs and the like, the efforts required for direct manual operation 35 of the rudder, are generally too great to be convenient in practice. Follow-up controls for steering motors hitherto have been relatively too expensive to install on such comparatively small craft. Additionally, in many of such systems the operator was unable to obtain a "feel" of the 40 controlled mechanism.

It is among the objects of the present invention to provide a force amplifying follow-up system in which a relatively large power is developed in response to the application of relatively small power, with the operator retaining the "feel" of the controlled mechanism; to provide such a system in which a force responsive device is inserted in a manually controlled element and controls the operation of a power mechanism in proportion to the direction and magnitude of the force exerted on such element; to provide such a system in which an electromagnetic force responsive device is incorporated with a manually controlled element and controls the operation of an electric motor operated mechanism in accordance with force exerted on the manually controlled element; to provide such a system including a manual operating mechanism, a power operated mechanism, an electric motor, electromagnetic torque responsive clutches, and means responsive to the force exerted on the manually operated mechanism for engaging and disengaging such clutches with a force exerted on the manually operated mechanism; and to provide a relatively simple, reliable, follow-up or servo-motor system having relatively few parts and which is accurately responsive to manually controlled force.

These and other objects, advantages and novel

features of the present invention will be apparent from the following description and the accompanying drawing. In the drawing:

Fig. 1 is a diagrammatic illustration of the invention as applied to a steering system for a dirigible craft.

Fig. 2 is a diagrammatic illustration of a portion of the system shown in Fig. 1, illustrating a modified form of the invention.

Fig. 3 is a diagrammatic illustration of another embodiment which the invention may assume in practice.

While the present invention is capable of many different applications, it will, for purposes of illustration, be described as applied to servomotor mechanisms. In accordance with the invention, a force responsive member is incorporated in a manually operated force transmitting means. The force responsive member preferably has a response of an electric nature, such as developing a predetermined voltage proportional to, or a certain function of, the manually applied force. Such voltage is used through the instrumentality of an electronic amplifier to effect operation of a power mechanism with a force proportionate to that exerted manually to operate the controlled element.

Preferably, the force responsive member comprises an electromagnetic member inserted in a control cable or rod and in which the magnetizing current through the element is proportional to the amount of tension or pressure exerted on the element. Such pressure or tension may effect a variation in an air cap of the electromagnetic member or may exert a variation in the magneto-strictive properties of the member. The variation in such properties of the member effects a variation of the potential applied as the input to an electronic amplifier, e. g., a push-pull amplifier to develop an amplified output controlling the engagement of one or the other of a pair of electromagnetic torque-responsive or slipping clutches connecting an electric motor to power driven devices for effecting control movements.

Referring to Fig. 1, the invention is illustrated as incorporated in a power steering arrangement for a controlled element, such as a rudder 10 which may be the steering element of a water borne craft or an airplane. Rudder 10 is pivoted on a rudder stock 11 to which is secured a cross bar 12. Cross bar 12 is operated by means of force-transmitting means, such as cables having their respective ends 13 and 14 wound respectively around power driven drums 15 and 16 and secured at their other ends 13a and 14a to force responsive members 20 and 25 respectively. Such cables each have several turns wrapped round their respective drums, the ends 13 and 14 being herein referred to as the "output" ends, and the ends 13a and 14a, as the "input ends." A manually operated force-transmitting means, such as cable 17 has each of its ends secured to one of the elements 20 or 25 and has several turns wrapped around the steering drum 18, being guided to the drum by suitable means such as pulleys 21 and 22. Drum 18 is secured for rotation with a shaft 23 on the outer end of which is a suitable manually operated member, such as a steering wheel 65. For a purpose to be described hereinafter, a braking drum 26 is mounted on the inner end of shaft 23 and adapted to be engaged by a normally disengaged, solenoid operated brake 27. A spring 28 normally urges brake 27 out of en-

gagement with drum 26. Brake 27 may be engaged with the drum by closure of a switch 30 which connects a suitable source of current such as a battery 31 in circuit with a solenoid 32 operatively associated with brake 27.

The power operating mechanism includes an electric motor 35 connected by leads 36 to a suitable source of electric current. Gearing 37 connects the output shaft of motor 35 to rotate a bevel pinion 38. Pinion 38 engages contrarotating bevel gears 41 and 42 secured to shafts 43, 44 respectively. Shafts 43, 44 are each connected to the driving members of one of a pair of electromagnetic torque responsive clutches 40 or 45 which may be of the type disclosed in said Patent No. 2,267,114. Driven members of clutches 40 or 45 are connected respectively to drums 15 and 16. Normally, and as will later appear, clutches 40 and 45 are engaged. However, if the clutch currents are equal, rotation of pinion 38 and gears 41, 42 by motor 35 is ineffective to operate drum 15 or 16, the clutches merely slipping.

In the arrangement shown in Fig. 1, the force responsive elements 20 and 25 comprise C-shaped magnets having air gaps 46, 47 and provided with coils 51, 52 around one leg of each magnet. Coils 51, 52 each have one terminal connected to a suitable source of current indicated at 50 which is preferably alternating current. The other terminals of coils 51 and 52 are connected, in series with resistors 53, 54 respectively, to the opposite terminal of source 50 which is grounded at 55.

Resistors 53, 54 are each connected across half of the input circuit of a duo-triode thermionic amplifier tube 60. For this purpose, dual cathode 61 is connected by a conductor 62 to the junction point of resistors 53, 54. The outer terminals of the resistors are respectively connected to the control grids 63, 64 of the tube. Anodes 66, 67 are respectively connected to one terminal of each of the electromagnetic clutches 40 and 45. The other terminals of these clutches are commonly interconnected to one terminal of a suitable source of current such as a battery 68. A pair of loss pass condensers 71, 72 are connected across the output circuits of tube 60 to smooth the current flow through the electromagnetic clutches. The other terminal of source 68 is connected to dual cathode 61. The foregoing arrangement constitutes a push-pull, i. e. phase-responsive, amplifier.

The described arrangement operates in the following manner. Motor 35 is energized to continually rotate pinion 38 and gears 41, 42. In the condition of the apparatus shown in the drawing, i. e. no force is being applied to the steering wheel, no rotation of drums 15 or 16 is effected as the current in clutches 40 and 45 are equal.

Magnets 20 and 25 are made of suitable resilient or elastic material, such as steel, so that a tension exerted thereon will vary the air gaps 46 or 47. It will be understood, however, that the magnets are of such dimensions, and the material thereof so selected, that the elastic limit of the material is not exceeded. Otherwise the resultant permanent deformation would affect the working of the system. Moreover it will be understood that a change in the length of the air on the order of 0.010" may, by the use of a suitable electronic amplifier, produce a change in the current through the magnet coil sufficient to operate the clutch exciting winding. The preliminary adjustment is such that each of the devices 20 and 25 is preset under a moderate ten-

sion so that rotation of the wheel 65 will increase or decrease the respective air gaps from a predetermined normal.

Assuming that the rudder is amidships and that the helmsman is applying no effort to the wheel 65 the tensions prevailing in input ends 13a and 14a on the one hand and that in the output ends 13 and 14 will be equal. Also the gaps 46 and 47 and the reluctance of the magnetic circuits of devices 20 and 25 will equal. Accordingly the parallel circuits forming the respective inputs to the push-pull amplifiers described will carry equal quiescent currents, and the potential drop across each of the resistors 53 and 54 will be equal. Since this will result in balanced output currents each clutch winding will carry the respective plate circuit quiescent current. However the output quiescent current may be selected low enough to maintain the clutches deactivated, or high enough to maintain the clutches in continued rotation. The latter is preferred in order that rotation of the clutches need not be initiated from standstill and interrupted at some frequency which will result in premature wear thereof.

With equal inputs to the two sides of the push-pull amplifier, and consequent equal outputs, both drums 15 and 16 will be rotated at the same speed and will be effective to convert a force f on each input end 13a and 14a into a force F at each output end 13 and 14. But since f and F are both equal on both sides of the system, there exists no resultant torque on the rudder 10. Assuming now that the helmsman applies an effort to the wheel 65 in such a direction that a tension is applied to element 20, this will increase air gap 46 causing a corresponding increase in the reluctance and in the magnetizing current flowing in coil 51. As a result, the potential drop across resistor 53 is increased and that across the resistor 54 is decreased. Upper half of the tube 60 will conduct more, and lower half will conduct less. Consequently the torque transmitted through clutch 40 to drum 15 will be increased, and that through clutch 45 to drum 16 will be decreased. As a result the tension in cable ends 13 and 13a will be increased, and that in cable ends 14 and 14a decreased, the increase and decrease being substantially equal in amount.

The tension in the cable ends 14 and 14a being reduced will permit a closure of the gap 47, a corresponding decrease in reluctance, and a reduced output from the lower side of the amplifier. Clutch 45 will have its torque lowered and drum 16 will rotate at a speed slower than drum 15. This will result in predominance of the upper half of the apparatus, and the rudder will be rotated counter-clockwise.

From the foregoing it will be obvious that reverse movement of the steering wheel will cause clockwise rotation of the rudder, with the lower half of the apparatus taking the preponderant position.

With the invention arrangement the helmsman is able to simulate conventional direct manual steering, since, by exerting a weak effort the rudder may be maintained at a predetermined angle. To increase or decrease such angle requires only a corresponding rotation of the steering wheel and with a force just in excess of that required to maintain any then existing rudder angle.

In the event that the wheel 65 is left unintended with rudder displaced from middle position, the present invention may act in two different man-

ners. If switch 30 is open and thus brake 27 is disengaged from drum 26, the drum 18 and wheel 65 are free to turn under the effect of a relatively small difference of tensions existing in devices 20 and 25 due to hydrodynamic pressure on the rudder 10. Such relatively small difference in tensions are not sufficient to modify appreciably the air-gaps 46 and 47 to effect a power operation of the mechanism.

However, if it is desired to maintain a predetermined setting of the rudder, switch 30 is energized to engage brake 27 with drum 26 and thereby hold drum 18 stationary. Should the rudder now tend to turn in a counterclockwise direction, an increased tension will be exerted on magnet 25 and a decreased tension on magnet 20. The potential drops across resistors 53, 54 will thereby become unbalanced in the manner previously described. Such unbalance will effect an increased output through anode 67 of tube 60 which will increase the torque through clutch 45, and thus effect rotation of drum 16 in a manner to move rudder 10 clockwise back into its predetermined relation. In the first case, when brake 27 is released, the action of wheel 65 is exactly the same as if it were directly connected to rudder 10. In the second case, the action is the same as if a controlled moment were exerted on wheel 65. From the preceding description it will be apparent that a relatively small braking force applied to brake drum 26 is capable of holding the rudder at its predetermined angle.

Fig. 2 represents a modified form of the arrangement shown in Fig. 1, and similar reference characters have been used to designate identical parts. In this arrangement, however, force responsive elements 70 and 75 are inserted between cable 17 and cables 13a and 14a in place of elements 20 and 25. Elements 70 and 75 are loops of material having magnetostrictive properties, such as nickel. In such materials, the magnet permeability is altered under the effect of applied compression or tension.

Each magnetic element 10 or 75 is provided with a primary winding 71 or 72 which windings are connected in parallel across alternating current source 50 of substantially constant voltage. A secondary winding 73 or 74 is provided for each element 70, 75, each secondary winding having one terminal connected to a control grid 63 or 64 of tube 60 and the other terminal connected to ground 76 and through a biasing resistor 77 to dual cathode 61. The operation of the circuit shown in Fig. 2 is the same as that of the circuit shown in Fig. 1. If a tension is exerted on element 70, its magnetic permeability is changed effecting a change in the mutual inductance between the primary and secondary, an increase in its magnetizing current and a correspondingly increased potential impressed on grid 63. This in turn causes an increased output current to be developed from anode 66 affecting engagement of clutch 40 to operate drum 15. A similar effect takes place when cable 17 exerts a tension on magnetic element 75.

While an elastic magnetic member, such as a steel magnet and a magnetic member having magnetostrictive properties have been illustrated as suitable force responsive elements, other force responsive elements may instead be used. As such alternatives will be easily understood by those skilled in the art, they have not been illustrated in an effort to simplify the description of the invention.

Figs. 1 and 2 illustrate the invention as applied to steering mechanisms. However, the invention is not limited to such an application, and may be applied generally wherever an amplified force is to be developed in response to a relatively small applied force. An alternative arrangement is shown in Fig. 3.

In the system of Fig. 3, an electric motor 80 is provided with an armature shaft 81 to which a pair of bevel pinions 82, 83 are applied. The latter respectively drive a pair of bevel pinions 84, 85 connected to the driving members of a pair of electromagnetic, torque responsive clutches 86, 87. Pinions 88 and 90, connected respectively to the driven elements of clutches 86 and 87 are arranged to rotate a gear 91 secured to output shaft 92 in either direction. Motor 80 is continually energized from a suitable source of current through conductors 93. However, ordinarily no rotation of pinions 88, 90 or gear 91 occurs as clutches 86 and 87 are disengaged.

Driving engagement of the clutches is effected in the following manner. A magnetic structure 95 is shown as secured to a suitable fixed support such as a wall 96. Magnetic structure 95 comprises an E-shaped magnet having a base 97 from which projects an intermediate or central arm 98 disposed between the inturned ends of a pair of outer short arms 100, 101 providing air gaps 102, 103. A manually operable controlling member 105, such as a rod, is secured to arm 98 to move the same relative to arms 100, 101 to vary the relative dimensions of air gaps 102, 103.

A pair of magnetizing windings 106, 107 are mounted on arm 97 on either side of arm 98. One terminal of each coil is connected to a suitable source of alternating current illustrated at 108. The other terminal of source 108 is grounded at 110. The other terminals of coils 106 and 107 are connected across source 108 to ground through resistors 111, 112, respectively.

The potential drops across resistors 111, 112 are respectively applied to control grids 113, 114 of a duo-triode thermionic tube 115. Dual cathode 116 of tube 115 is connected to ground at 117 and to the negative terminal of a suitable source of current such as a battery 118. Anodes 120, 121 of tube 115 are each connected to a terminal of the energizing winding of one of the clutches 86 or 87. The other terminals of the clutches are commonly interconnected to the positive terminal of source 118. Low pass condensers 122, 123 are connected across both halves of the output circuit of tube 115 to filter alternating current components from the circuit including the energizing windings of clutches 86 and 87.

The described arrangement of Fig. 3 operates in the following manner. Assuming that a tension is placed on rod 105, air gap 102 will be decreased and air gap 103 will be increased. Consequently, the voltage drop across resistor 111 will be decreased and that across resistor 112, increased. As these potentials are impressed on the control grids of tube 115, the push-pull amplifier will be activated to effect a greater current flow to clutch 87 so that motor 80 will drive gear 91 and shaft 92 through pinion 90. The force exerted on shaft 92 will be proportional to the force exerted on rod 105 but will be greatly amplified with respect thereto. Rotation of shaft 92 will continue so long as a tension is exerted on rod 103. A similar effect takes place in the opposite direction when compression is applied to rod 105 to increase air gap 102 and decrease

air gap 103. It will be understood that, due to the nature of the push-pull amplifier here employed, the function will be similar to that described in connection with Fig. 1. That is to say, the quiescent current in each of the clutches 83 and 87 being equal, the gear 91 is, in the absence of a signal, forced to remain stationary.

The described invention provides a novel and simple servo-motor system in which a greatly amplified force is exerted proportional to a relatively small initiating force where the initiating force is manual, the operator retaining the "feel" of the control being performed. Complicated circuits and wiring are eliminated. If the arrangement is installed as a steering mechanism on water borne crafts such as yachts, tugs and so forth, no complicated mechanism between the pilot house and the steering motor is necessary, as all the electrical controls may be placed adjacent the steering motor. The force responsive members may be located at any point in the steering cable between the steering wheel and the power driven drums.

While specific embodiments of the invention have been shown and described in detail to illustrate the application of the principles thereof, it will be understood that the invention may be otherwise embodied without departing from such principles.

What is claimed is:

1. Torque amplifying apparatus comprising, in combination, a member for controlling a controlled element by the application to said member of a relatively small force variable in direction and magnitude; mechanism, including frictional clutch means and a source of power, for impressing on the controlled element a relatively large force variable in direction and magnitude; and control means for said mechanism including magnetic force responsive means operatively associated with said member; said control means continuously controlling the degree of engagement of said frictional clutch means to control the force exerted on the element by said mechanism in accordance with the direction and magnitude of the force applied to said member as measured by said force responsive means.

2. Torque amplifying apparatus comprising, in combination, a device for controlling a controlled element by the application to said member of a relatively small force variable in direction and magnitude; mechanism, including frictional clutch means and a source of power, for impressing on the controlled element a relatively large force variable in direction and magnitude; and control means for said mechanism including electromagnetic force responsive means operatively associated with said member; said control means continuously controlling the degree of engagement of said frictional clutch means to control the force exerted on the element by said mechanism in accordance with the direction and magnitude of the force applied to said member as measured by said force responsive means.

3. Torque amplifying apparatus comprising, in combination, a manually operable member for controlling a controlled element by the application to said member of a relatively small force; power drive means; electromagnetic clutch means operatively interposed between said power drive means and said force transmitting means; electronic means controlling the engagement of said clutch means; a linkage connected to said member for transmitting said force to a magnetic member forming a force-responsive ele-

ment in said linkage, said magnetic member having a reluctance variable in accordance with the force exerted by said manually operable member; magnetizing winding means on said magnetic member and connected in circuit relation with a source of power, the magnetizing current through said winding means varying in accordance with the reluctance of said magnetic member; and circuit means for varying the input to said electronic means proportionately to the change in magnetizing current through said winding means, whereby correspondingly to vary the output of said electronic means to vary the degree of engagement of said clutch means so that said power drive means will impress an amplified force on the controlled element proportional to the force applied to said manually operable member.

4. Apparatus for amplifying a mechanical force for actuating a controlled element, comprising, in combination, a magnetic member having a reluctance variable in accordance with the force exerted on said member; a manually operated member for impressing on said member a relatively small force variable in direction and magnitude to vary said reluctance; mechanism for impressing a relatively large force on the controlled element; and electromechanical means, including a reversible servo mechanism and a phase-responsive amplifier therefor, operatively connected to said magnetic member for controlling said mechanism in response to variations in said reluctance, to impress a relatively large force on the controlled element varying in direction and magnitude in accordance with the variations in direction and magnitude of the relatively manual small force impressed on said member.

5. Apparatus for amplifying a mechanical force for actuating a controlled element, comprising, in combination, a magnetic member having a reluctance variable in accordance with the force exerted on said member; magnetizing winding means on said magnetic member and connected in circuit relation with a source of power, the current through said winding means varying in accordance with said reluctance; an element for impressing on said member a relatively small force variable in direction and magnitude to vary said reluctance; mechanism, including a source of power and electromagnetic slipping clutch means, for impressing a relatively large force on the controlled element; phase-responsive electronic amplifier means controlling the engagement of said clutch means; circuit means including said winding means for impressing on the input of said electronic means a potential proportional to the magnetizing current through said winding means, whereby to correspondingly vary the output of said electronic means to accordingly vary the engagement of said clutch means so that said mechanism will impress an amplified force on the controlled element proportional to the engagement of said clutch means.

6. A system for actuating the steering element of a dirigible vehicle comprising, in combination, a manually operable steering member; a steering drum connected thereto; a steering cable having an intermediate portion engaged on said drum and connected at both ends to the vehicle steering element; a pair of power driven drums respectively engaged with said cable on either side of said steering drum; a power drive means; reversing-type gearing means operable by said power drive means; a pair of electromagnetic slipping clutches respectively connecting said

gearing to each of said power driven drums; phase-responsive electronic means controlling the energization of said clutches; a pair of magnetic members respectively incorporated in said cable on either side of said steering drum and between the same and said power driven drums; said members having air gaps variable in accordance with forces exerted on said cable by said member or by the steering element, and the reluctance of said members varying in accordance with the variations in said air gaps; a pair of magnetizing windings each respectively associated with one of said magnetic members and connected across a source of potential, the magnetizing current through said windings varying in accordance with the reluctance of said members; and circuit means for applying to said electronic means a signal potential corresponding to the potential drop across said windings, whereby said clutches will be differentially energized to impress on the steering element, through said power driven drums, a force variable in direction and magnitude in accordance with the direction and magnitude of the force exerted on said cable by said steering device.

7. Apparatus for amplifying a relatively small force applied to a manually operated member for actuation of a controlled element, comprising, in combination, a relatively fixed magnetic member of elastic material of E-configuration, the end legs thereof projecting toward each other to provide an air gap and the central arm thereof being positioned in said air gap; said manually operated member being connected to said arm for impressing a relatively small force thereon to vary the position of said central arm in the air gap; a pair of magnetizing windings on said magnetic member on either side of said central arm and connected across a source of potential, the magnetizing current through said windings varying in accordance with the relative position of said central arm in the air gap; mechanism, including electromagnetic slipping clutch means, for impressing a relatively large force on the controlled element; phase-responsive electronic means controlling the energization of said clutches; circuit means for applying to said electronic means a signal potential corresponding to the current through said windings, whereby said clutches will be differentially energized to impress on the controlled element an amplified force variable in direction and magnitude in accordance with the direction and magnitude of the force exerted on said central arm.

8. In a system for controlling a controlled member a torque amplifying device comprising an input end to which a relatively small torque may be applied, an output end for providing an amplified version of said input torque for application to the controlled member, means associated with said input end for measuring the input torque, said means including a ferromagnetic member and flux producing means therefor, the magnetic field being variable in response to mechanical force applied to said ferromagnetic member, power driven means operatively connected to said

output end, and circuit means including said flux-producing means, an electronic amplifier and servo-mechanism for actuation of said power driven means in response to the force measured by said measuring means, whereby a substantially proportional and continuous relation between the input torque and the output torque may be obtained.

9. Apparatus for amplifying a relatively small force for actuation of a controlled member with an amplified version of said small force comprising in combination an electromagnetic device including a core having a gap therein and a magnetizing winding, a member connected to said core and to which the small force may be applied for varying the reluctance of the magnetic circuit proportionately to the small force and thus to vary the current in said winding, an electronic amplifier having said winding connected in the input thereof, a power source, electrically-operated clutching means for connecting the controlled member to said source, said clutching means being connected in the output circuit of said amplifier.

10. Torque amplifying apparatus comprising in combination a member for controlling a controlled element by the application to said member of a relatively small force equivalent to an input torque, means including a deformable element and an electrically conducting element, means associated with said deformable element, force-transmitting means interconnecting said member and deformable element for translating movement of said member into a varying current through said electrically conducting element, power driving means, electrically operated clutch means for selectively clutching said power means to said controlled element for moving said controlled element pursuant to an amplified version of the input torque, a current source, an electronic amplifier, and an electrical circuit including said conducting element, clutching means, amplifier current source, for moving said controlled element pursuant to an amplified version of the input torque.

NICHOLAS MINORSKY.
